UNITED STATES PATENT OFFICE.

HERBERT E. WHITE, OF YOUNGSTOWN, OHIO, ASSIGNOR TO THE GENERAL FIREPROOF-
ING COMPANY, OF YOUNGSTOWN, OHIO, A CORPORATION OF OHIO.

EXPANDED-METAL STRUCTURE.

1,008,877.

Specification of Letters Patent. Patented Nov. 14, 1911.

Application filed February 3, 1911. Serial No. 606,368.

To all whom it may concern:

Be it known that I, HERBERT E. WHITE, of Youngstown, Mahoning county, Ohio, have invented a new and useful Improvement 5 in Expanded-Metal Structures, of which the following is a full, clear, and exact description; reference being had to the accompanying drawings, forming part of this specification, in which—

10 Figure 1 is a perspective view of a portion of a blank used in the manufacture of my invention; Figs. 2 and 3 are similar views illustrating successive operations upon the blank; Fig. 4 is a plan view of a portion 15 of the expanded structure; and Fig. 5 is an end view of the same.

My invention has relation to expanded metal structures, and more particularly to structures which are adapted for use in 20 building construction either for lathing or reinforcing purposes.

One objection to material of this kind has been that when used in a roofing or floor 25 there is not sufficient metal in it to give the desired reinforcing action; and the object of my invention is to provide a structure of this character having an increased amount of metal therein, whereby the objection is overcome.

30 In the manufacture of structures under my invention, I take a sheet metal blank of any desired width, and which has rolled therein any desired number of solid longitudinally extending reinforcing ribs 2, these 35 ribs being preferably though not necessarily of such form that they will project equally at both sides of the metal sheet. The sheet is next subjected to a die or pressing action to give it the form shown in Fig. 2, in which 40 it has a plurality of deep ribs 3. In the structure illustrated in the drawing, the ribs 2 are so located that when the ribs 3 are formed the ribs 2 will lie at the bottom of the ribs 3. This feature is not, however, 45 essential to my invention, since the ribs 2 may be located at any part of the completed structure intermediate the expanded sections thereof. It will also be obvious that any desired number of the ribs 2 may be em- 50 ployed to be disposed at different places on the finished structure. The sheet having the form shown in Fig. 2 is then subjected to the action of cutters, which make the cuts 4 indicated in Fig. 3, and at the same time

preferably form the short reverse bands 5 55 at the upper edges of the deep ribs 3, and also form intermediate each two adjacent series of cuts a shallow rib 6, which faces toward the same side of the structure as the reverse bends 5. The sheet is then expanded 60 in any usual or suitable way to form the finished structure, a portion of which is shown in Figs. 4 and 5. The provision of the shallow ribs 6 and the reverse bends 5 cause the slats 7 of the expanded sections to form half 65 bends or twists in the expanding operation, which greatly strengthens the structure.

It will be understood that my invention is not limited to the precise form of structure which I have shown in the drawings, but is 70 applicable generally to the expanded metal structures of this general class, in which it is desirable to provide the structure with an increased amount of metal for reinforcing purposes.

75 What I claim is:—

1. An expanded metal structure formed from a plate of a non-uniform section having bar portions, the sheet portions between the bars having expanded sections and the 80 bar portions being bent out of the flat plane of the sheet to form deep ribs along which the bars extend longitudinally to constitute reinforcements, substantially as described.

2. An expanded metal structure formed 85 from a plate of non-uniform section having bar portions, the bar portions projecting at both sides of the flat plane of the sheet, the sheet portions between the bars having expanded sections, and the bar portions being 90 bent out of the flat plane of the sheet to form deep ribs along which the bars extend longitudinally to form reinforcements; substantially as described.

3. An expanded metal structure having 95 expanded portions and non-expanded corrugated portions, the latter having solid longitudinally extending ribs, portions of which project at each side of the metal forming the corrugations; substantially as 100 described.

In testimony whereof, I have hereunto set my hand.

HERBERT E. WHITE.
